UNITED STATES PATENT OFFICE.

HUGO L. HEZINGER, OF EWING, MISSOURI.

DESIGN FOR A ROPE CURTAIN.

51,121.

Specification for Design. Patented Aug. 7, 1917.

Application filed March 10, 1917. Serial No. 154,066. Term of patent 14 years.

To all whom it may concern:

Be it known that I, HUGO L. HEZINGER, a citizen of Germany, residing at Ewing, in the county of Lewis and State of Missouri, have invented a new, original, and ornamental Design for a Rope Curtain, of which the following is a specification, reference being had to the accompanying drawing, forming a part thereof.

The figure is an elevation of a curtain showing my new design.

I claim:

The ornamental design for a rope curtain, as shown.

HUGO L. HEZINGER.
